DESIGN FOR A CIGAR AND CIGARETTE CASE OR SIMILAR ARTICLE.

52,829.

Specification for Design. Patented Dec. 31, 1918.

Application filed May 2, 1918. Serial No. 232,169. Term of patent 3½ years.

To all whom it may concern:

Be it known that I, FRANK B. NICHOLS, a citizen of the United States, and resident of the borough and county of the Bronx, city and State of New York, have invented a new, original, and ornamental Design for Cigar and Cigarette Cases or Similar Articles, of which the following is a specification.

Reference is to be had to the accompanying drawing which shows an example of my design for illustrative and descriptive purposes and in which Figure 1 is a view of one face of a case showing my design; Fig. 2 is an edge view; and Fig. 3 is a view of the opposite face of said case including my design.

The design consists of a ribbon 6 emblematic of a branch of the Army or Navy and extending in predetermined relation to opposite edges of the case 5; the ribbon 6 is located between borders 7 of gold, silver or other braid. A metallic shield 8 may be combined with the ribbon as shown in Fig. 1.

I claim:

The ornamental design for a cigar and cigarette case or similar article as shown and described.

In testimony whereof I have hereunto set my hand.

FRANK B. NICHOLS.
